APPARATUS FOR BINDING PERFORATED LEAVES

Emil N. Farkas, Chicago, Ill., assignor to Farkas Binding Trust, Chicago, Ill.

Application April 20, 1943, Serial No. 483,713

6 Claims. (Cl. 11—1)

This invention relates to new and useful improvements in apparatus for binding marginally perforated leaves by means of flexible comb-shaped elements.

Flexible fingers projecting from the backs of such combs are laced through the marginal perforations of book leaves and then anchored by means of a locking strip which may or may not be physically united with the comb back. The combs are preferably of the types disclosed in my prior patents, No. 2,206,394, of July 2, 1940, No. 2,265,276, of December 9, 1941. The machine for lacing the combs through the book-leaves and anchoring them is an improvement on the one disclosed in my prior Patent No. 2,239,036, of April 22, 1941. The specific comb structures disclosed in the last-mentioned patent were of the kind in which the preferred form showed the locking strip physically separated from the comb back, whereas I shall here disclose apparatus for handling combs in which preferred embodiment showed the locking strip is integral with the comb back, like the one disclosed in my Patent No. 2,265,276.

In accordance with the present invention, the ends of the comb fingers are bent and forced in a folded condition through slits in the locking strip which, as above stated, is physically connected with the back of the comb. The finger ends are so shaped that this operation will lock them in place.

The invention will now be described in detail as applied to the drawings in which—

Fig. 1 is a front view of one embodiment of the invention;

Fig. 2 is a side elevation;

Figs. 3 and 4 are side elevations of the comb-inserting mechanism in two successive positions;

Fig. 3a is a side elevation of the drive for the forks by means of which the binding fingers may be anchored to the backs; and

Figs. 5, 6 and 7 are perspective views of three successive positions of the forks.

As explained in my Patent No. 2,265,276 and as shown in Figs. 5-7, marginally perforated leaves 1 are bound by inserting through the perforations teeth or fingers 2 of a binder shaped as a comb and having a back 3. Near their ends, the fingers 2 of this comb (made out of paper) have two sloping slits 4. When distorted along the slits 4, the end 5 of each finger can be doubled back (Fig. 6) and forced through a suitably aligned U-shaped slit 6 in the back 3 (Fig. 7). The distorted ends 5 will anchor the teeth 2 against withdrawal from the back 3.

The paper combs are stacked in a suitable reservoir (not shown) from which they are fed on a comb-shaped clamping plate 7 to which is hingedly connected another comb-shaped clamping plate 8 by pin 9 (Fig. 2). The two clamping plates are supported in a carriage frame 10 which slides vertically up and down in direct response to movement of treadle 11. The clamping plates are located above a table 12 on which are placed the perforated book leaves 1. The plate 7 is so positioned that the teeth 2 of the paper binding comb, the back 3 of which is suspended from three prongs 13 projecting through the teeth of plate 7, will be above leaves 1 and aligned with the perforations thereof (Fig. 2).

The operator depresses the treadle 11 on the end of a lever 14 pivoted to the frame 15 at 16. The lever 14 is normally held up by a coiled spring 17 and when pushed down causes through a pivoted link 18 a bell crank lever 19 to rotate counter-clockwise around its pivot point 20. This will rotate counter-clockwise on its pivot 22 a yoke 23 fastened to lever 19 at 24 and linked at 22 to a lug 25 projecting from a platform 26, producing a downward movement in platform 26 against the tension of spring 26a, to which are attached clamping plates 7 and 8 by their hinge 9. As clamping plate 8 is forced downward, it is also rotated clockwise around its pivot 9 by a fixed cam pin 27 and thus caused to move towards clamping plate 7 (Fig. 2).

The counter-clockwise rotation of yoke 23 produces a downward movement of its pivot 22 which continues until the hooked end 29 of an arm 28 fastened to yoke 23 and projecting through the platform 26 engages an apron 30 (Fig. 3).

During the continued rotation of yoke 23, the clamping plates 7 and 8, with the paper comb suspended by lugs 13 between them, are moved vertically downward and rotably toward each other. The marginal perforations in the leaves 1 are aligned with the teeth of the comb assembly and thus the teeth 2 of the paper comb are guided through the leaf perforations.

As shown in Fig. 3, at the end of the downward movement and the tips 5 of teeth 2, the lugs 13 will have been withdrawn and lugs 13a will thrust the comb down with ends 5 projecting beyond the ends of the clamping or guiding plates 7 and 8. When the rotation of a shaft 31 is started, as will be described, the three lugs 13 are withdrawn from the clamping plate 7. This action is effected by a tensional relation between the rod 33 and the lever 32 (Fig. 2). During the

downward movement of the plate 7 the rod 33 imparts a clockwise pressure upon lever 32, and thereby a like pressure upon its rigidly connected member 35, thus maintaining the lug 13 in a supporting relation to the paper comb. However, subsequently, during progress of the downward stroke, when the curved portion 32-a of the lever 32 contacts the rod 33, the lever 32 receives a rotary impulse from the tensioned rod 33, in a contra-clockwise direction. This produces a contra-clockwise rotation of member 35, thus removing support of lug 13 from paper comb and causing lug 13-a to rotate in a counter-clockwise direction. It is this downward pressure of lug 13-a upon the upper edge of back 3 of comb which displaces the paper comb downward, beyond its original position between the plates 7 and 8, thus exposing the projecting ends 15 of the paper comb to the deforming process of plate 36, as shown in Fig. 3. The paper comb is now allowed to drop down and will, as a matter of fact, be pushed down by the counter-clockwise rotation of these hooks 35 which will project through the teeth of clamp 7 with their upper lug ends 13a and bear down on the upper edge of the comb back 3 (Fig. 3). This latter action forces the paper finger ends 5 to project down below the clamping plates 7 and 8, thus enabling a platform 36 to bend these ends.

When the hooked end 29 of the bar 28 engages the apron 30, it will cause the normally tilted shelf 36 (Figs. 2 and 3) to swing around pivot 37 into a horizontal position (Fig. 3). Metal fingers 38 bent into semi-circles are fastened to a transverse shaft 31, in alignment with the comb teeth. The fingers 38 have forked ends 39 arranged to engage at the slits 4 in the comb teeth projecting below the clamping means. The ends 5 of the paper combs are contacting the tilted shelf 36 and are still engaged by the clamping means 7 and 8, which prevents their movement backward. The forked ends 39 of fingers 38 will, therefore, bite into the comb teeth at the slits 4.

When the shelf 36 is in the position shown in Fig. 3, the ends 5 of the comb teeth will be bent at right angles and clamped between the shelf and the fingers 38. Later, during the continued rotation of shaft 31, the wedges formed within the forked ends 39 of fingers 38 will grip the comb teeth within the slits 4. The comb teeth will thus be rotated counter-clockwise away from the shelf 36, the ends 5 of the comb teeth being doubled back against fingers 38 (Fig. 6).

The operator now releases treadle 11. Spring 17 will return it, and thus the elements connected with it to normal, the above-described operations being performed in reverse. This upward movement of the treadle 11 and the resulting upward movement of carriage frame 10 provides power for the rotation of shaft 31 on which are mounted the curved metal fingers 38. This is accomplished by a rack gear fixed on carriage frame 10, the motion of which is transmitted through gears 40, 41, to a pinion gear 42 keyed to shaft 31.

While the fingers 38 rotate, the clamping plates 7 and 8 are moved upwards into the position shown in Fig. 4 by means of the tension in a spring 17 which raises lever 14 and thereby reverses the action of members 18, 19 and 23, causing plates 7 and 8 to rise and finally causing plate 7 to open out again, due to resistance of strut bar 33, into the position shown in Fig. 2.

The rotation of fingers 38 is continued until

they project through the U-shaped slits in the comb back 3 (Figs. 4 and 7). Thus the folded back ends 5 of the teeth will be forced through the back 3, the ends 39 of the fingers 38 opening the flaps formed by the U-shaped slits 6. The ends 5 of the comb teeth remain anchored in back 3 by virtue of the deformation of the ends along the slits 4 and the transverse fold formed as shown in Fig. 7.

10 A stop 43 having perforations 44 aligned with fingers 38 is provided behind the back 3 when the paper comb is dropped through the perforations in the leaves 1. This stop is moved horizontally into contact with the back 3 to prevent it from folding back and down when fingers 38 push against it. This may be performed by suitable means connected with the mechanism or manually by the operator.

20 The bound book leaves may be removed and the operation repeated.

What is claimed is:

1. In a device for fastening to a slotted strip the ends of binder fingers projecting through marginally perforated leaves, a plurality of forks, one for each finger, means for forcing each fork transversely to straddle its corresponding finger near its end with the finger end partly folded along the line of engagement by the fork, means for moving the forks and strip relatively to one-another until the forks with the finger ends project through the slits in the strip, and means for withdrawing the forks from the slits.

2. In a device for fastening the ends of binder fingers to a slotted back by which they are held together, said fingers being slit near their ends and projecting through marginally perforated leaves, a plurality of forks, one for each finger, means for moving each fork to engage its corresponding finger at its slit end and partly folding the finger end, means for moving the forks and back relatively to one-another until the forks with the folded finger ends project through the slits in the back, and means for withdrawing the forks.

3. In a device for binding marginally perforated leaves with paper combs having flexible fingers provided with lateral slits near their ends slanting towards the tips of the fingers and U-shaped slits in the back aligned with the finger, two relatively rigid open-ended guides of about the same contour as the fingers and spaced from one-another, a plurality of movable lugs projecting between the guides and on which a comb is suspended, means for moving the guides towards one-another to clamp the comb fingers, a table for supporting the leaves, the perforations of which are aligned with the guides, means for releasing said lugs and projecting the finger ends from the guides, a tiltable platform below the surface of the table and normally at an angle to the horizontal but generally in a plane outside of the plane of the fingers clamped between the guides, means for moving the guides through the perforations in the leaves, means for removing the guides from the perforations of the leaves and allowing the comb to hang with the edge of the back engaging the top leaf and the finger ends adjacent the platform, a movable stop engaging the back of the comb and having openings aligned with the U-shaped slits, means for tilting the platform into a substantially horizontal position folding each finger end along a line connecting the bottoms of the slits, a plurality of forks, one for each finger moved parallel with the folded finger ends to straddle each finger in

its fold and to grip it, means for moving said forks and stop relatively to one-another until the folded finger ends and the gripping forks project through the U-shaped slits in the comb back into the openings of the stop, and means for withdrawing the forks from the slits.

4. In a device for binding marginally perforated leaves with paper combs, having flexible fingers provided with lateral slits near their ends slanting towards the tips of the fingers and U-shaped slits in the back aligned with the finger, two relatively rigid open-ended guides of about the same contour as the fingers and spaced from one-another, a plurality of movable lugs between the guides from which a comb may be suspended, means for moving the guides towards one-another to clamp the comb fingers, a table for supporting the leaves, the perforations of which are aligned with the guides, means for moving the guides with the comb fingers through the perforations in the leaves, means for removing the guides and releasing the comb to hang with the edge of the back engaging the top leaf and the finger ends adjacent the platform, a stop against which the back of the comb rests and having openings aligned with the U-shaped slits, a plurality of forks, one for gripping each finger at its slits, means for moving said forks horizontally and vertically, means for moving said stop to move the back towards the forks until they pro-

ject through the U-shaped slits in the comb back into the openings of the stop, and means for withdrawing the forks from the slits.

5. In a device for fastening to a slotted strip the ends of binder fingers projecting through marginally perforated leaves, a plurality of clamping means, one for each finger, means for forcing each clamping means transversely to straddle its corresponding finger near its end with the finger end partly folded along the line of engagement by the clamping means, means for moving the clamping means and strip relatively to one-another until the clamping means with the finger ends project through the slits in the strip, and means for withdrawing the clamping means from the slits.

6. In a device for fastening the ends of binder fingers to a slotted back by which they are held together, said fingers being slit near their ends and projecting through marginally perforated leaves, a plurality of clamping means, one for each finger, means for moving each clamping means to engage its corresponding finger at its slit end and partly folding the finger end, means for moving the clamping means and back relatively to one-another until the clamping means with the folded finger ends project through the slits in the back, and means for withdrawing the clamping means.

EMIL N. FARKAS.
